UNITED STATES PATENT OFFICE

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA

DOUBLE OFFTAKE FOR COOKING RETORTS

Application filed January 12, 1925. Serial No. 1,718.

This invention relates broadly to improvements in the heat treating art and more particularly to improvements in means and methods for the discharge of distillation products from carbonizing plants and the like, such, for instance, as the by-product vertical coking retort battery disclosed in my copending application Serial No. 684,342, filed January 4, 1924.

10 The gases taken off the fresh coal in the upper regions of the coking chambers of such batteries are very rich, or high in B. t. u. value, whereas the gases which are generated in the lower regions of the coking chambers, principally by the action of steam on coke, are lean, or low in B. t. u. value. Economy of operation requires that both the rich and the lean gases be saved and it has heretofore been the usual practice to take off both of these gases into a common main. Since in coking retorts, particularly those of the continuous vertical type exemplified in my aforementioned application, there is an extensive region near the top in which the coal becomes pasty and obstructs the passage of the hot lean gases from below, it has heretofore been a practice to pass these gases through vertical passages in the chamber wall connected with the offtakes for the rich gases above, the rich gases being in part decomposed by the high heat imparted to the mixture by the lean gases resulting in the lowering of the B. t. u. value of the mixture, the tar present also being in part decomposed causing formation of carbon and pitch and so obstructing the passageways for the gas. Since most municipalities in this country require that the gas sold to the public be of a relatively high B. t. u. value, by-product vertical retorts have not become common commercial practice here although they have found a more extensive use abroad where the requirement as to B. t. u. value of the gas is less severe.

15 The aforementioned difficulties are essentially overcome and the use of vertical retorts yielding a gas mixture of the desired B. t. u. value rendered commercially practicable by my invention which involves broadly means and methods for separating

the rich and lean gases to prevent the decomposition of the richer gases and to remove the tar and other foreign matter therefrom substantially without the formation of the objectionable carbon and sticky pitch and for 55 subsequently mixing the rich and lean gases in the proportions necessary to give the desired B. t. u. value to the mixture while separately collecting the remainder of the lean gas, if any, and the precipitate from both the 60 rich and the lean gas for special uses, or, if desired, separately collecting the rich and lean gases in their entirieties.

20 As a specific embodiment of my generic invention I may employ an upper gas offtake 65 preferably provided with a cooling agency such as a liquid spray device, a lower gas offtake definitely located below the region of pasty material in the retort chamber, a ledge 70 preferably being formed in the chamber wall and the walls thereabove being tapered inwardly to facilitate the accumulation of gas, and a stand pipe exterior of the retort structure communicating with both of said offtakes. The stand pipe may also communicate at its top with a gas collecting main and at its bottom with a second gas and flushing liquor collecting main. Other cooling devices 75 may, if desired, be provided, as for instance, a reverse steam nozzle or the like, in the lower offtake designed to cool the same and prevent undue expansion of the offtake pipe and disruption of the wall structure. An additional cooling agency, such as a spray 80 may be located in the upper gas collecting 85 main above the opening between the latter and the stand pipe. I also preferably provide in the stand pipe, a regulating device such as a butterfly valve between the upper 90 gas main and upper gas offtake and a pivoted liquid seal valve between the gas offtakes, which in raised position permits the passage 95 of the flushing liquor but prevents the passage of gas, and a similar valve below the lower gas offtake.

25 The invention further consists in such other new and useful improvements and has for further objects such other operative advantages or results as may be found to obtain 100

in the processes and apparatuses hereinafter described or claimed.

While, as a specific embodiment, I have disclosed the principles involved in my invention as applied to a vertical coking retort oven it will be obvious to those skilled in the art that they are applicable to ovens of other types or to other heat treating apparatus.

In the accompanying disclosure forming a part of this specification and showing, for purposes of exemplification, a preferred form and manner in which the invention may be embodied and practiced, but without limiting the claimed invention specifically to such illustrative instance or instances:

Figure 1 is a sectional view in a vertical plane transverse of the battery through a heating chamber showing certain details in elevation and the flues of a heating wall in dotted lines.

Fig. 2 is a vertical section on the line 2—2 of Figs. 4 and 5 showing a portion of a coking chamber and the ascension or stand pipe arrangement for taking off the gases therefrom.

Fig. 3 is a vertical section on the line 3—3 of Fig. 1 transverse of the coking chambers and heating walls showing the relation of the lower gas offtake to the coking chamber wall.

Fig. 4 is a front elevation viewed from the line 4—4 of Fig. 2 showing the arrangement of stand or ascension pipes, and upper and lower collecting mains.

Fig. 5 is a fragmentary top plan view of the battery, gas collecting main and ascension pipes viewed from the line 5—5, Fig. 2, and

Fig. 6 is a horizontal sectional view on the line 6—6 of Fig. 2, viewed from above, through the battery and the lower gas offtake.

The same characters of reference designate the same parts in each of the several views.

In the illustrated embodiment of the invention there is shown a coking chamber 11 alternating with heating walls 12, the sides of the oven being tapered inwardly towards the top as shown at 13 to facilitate the feeding of coal and also the taking off the gas at the base of the tapered portion. The outer ends of the respective coking chambers and heating walls are closed by the refractory wall structure 15. The heating walls comprise upper and lower flued portions 37 and 38 as shown in dotted lines in Fig. 1, communicating through suitable passageways with the regenerators 45, as more particularly described in my copending application above referred to. The battery is provided with a top 39. There is also provided a coke extractor 66 and regenerator reversing mechanism 67.

There is provided at the top of the coking chambers coal feed hoppers 70, preferably of cast metal, having tops 71 and bases 72, each of the latter being provided with a series of openings whose peripheries constitute seats

upon which rest flanges formed at the top of feed pipes 73, as shown more particularly in Figs. 1 and 3. The feed pipes thus admit a ready removal for cleaning and repair. Located between the feed pipes are guides 74 for the coal, of inverted V shape, and containing a passageway 75 to permit ventilation and cooling of the hopper. Between the several feed pipes are spaces 76 for the accumulation of gas. These spaces are connected to each other and to a gas pocket or offset space 77 leading to the upper gas offtake by passageways 78. Above each gas space 77 is seated a gas offtake nozzle 79 cast integral with the hopper base 72.

The gas offtake apparatus comprises the upper and lower offtake pipes 80 and 81 respectively, the former being connected to the gas offtake nozzle 79 in the hopper base at the extreme top of the coking chamber and the latter being connected with the coking chamber beneath a ledge 82 at the lower ends of the inclined walls 13 of the chamber to facilitate the accumulation and taking off of the gas. The upper and lower gas offtakes are connected with each other and with the upper gas collecting main 83 and the lower liquor and gas collecting main 84 by the stand pipe which may consist of several sections 85, 86, 87, 88 and 89; the sections 85 and 88 being preferably cast integral with sections of the upper and lower offtakes respectively. I prefer to provide the upper offtake with an inverted elbow pipe section 90 seated at one end in the offtake nozzle 79 on the hopper base and connected at its other end to the extension from the pipe section 85, and I may provide through the elbow of this pipe section tubes 91 carrying at their inner ends liquid spray nozzles 91¹ positioned to direct the spray down the outer leg of the elbow section. The offtake may also be provided at the apex of the elbow with a removable cover 92 to permit cleaning and inspection. In the pipe section 85, just above its connection with the upper offtake, is provided a butterfly valve 93 which permits the total shutting off of the gas collecting main 83 from the offtake when it is desired to clean the latter, or the partial shutting off of the gas main for regulation or other purposes. I also preferably provide in the gas collecting main 83 and above the opening therein leading to the pipe section 85, a spray nozzle 94 adapted to direct its spray downwardly through said opening.

At the end of the lower gas offtake, adjacent the coking chamber, I prefer to provide a cooling device adapted to project steam outwardly through said outlet and as a convenient means for effecting this result I may provide a tube 95 disposed axially of the lower gas offtake 81 and provided at its end adjacent the coking chamber with a reversing nozzle 95¹. This tube may be conveniently supported in the front wall of the stand pipe

section 88 and by a support 96 secured to the extension therefrom forming a part of the lower gas offtake. At a point in this extension adjacent the stand pipe I preferably 5 form a lip or baffle 97 to prevent flow of the spray liquid from above passing into the retort chamber through the lower offtake.

In the stand pipe section 87 I prefer to provide a liquid valve comprising the inverted 10 conical member 98 and the pivoted vessel member 99 of larger cross-sectional area than the base of the conical member. An operating handle 100 is provided exterior of the stand pipe for operating said pivoted vessel member, being connected thereto through its pivot. Inspection openings 101 may be provided in the stand pipe sections 87 and 88.

In the stand pipe section 89, I also prefer to provide a liquid seal valve 102—103, similar to the liquid seal valve 98—99, having an 20 operating handle 104 exterior of the stand pipe. Convenient inspection openings 101 may also be provided in this section.

My apparatus may be operated to effect 25 various results. For instance—the gas taken off from each off-take may be mixed as a whole to give a resultant mixture or the gases may be collected separately or a regulated quantity of the leaner gas from the lower off-take may be mixed with the richer gases taken off from the upper off-take, the rest of the leaner gas being taken off separately.

When it is desired to mix all of the gases from the respective offtakes, the liquid seal 30 valve 102—103 is closed and the liquid seal valve 98—99 is opened. The rich gases from the upper offtake 80 and the leaner gases from the lower offtake 81 will then commingle within the pipe section 85 and pass into the 35 gas collecting main 83. The gas from the upper offtake will be washed by the liquid spray device 91¹ which will remove the tarry and kindred substances therefrom and the drain liquor will thereupon pass down the stand 40 pipe and overflow the liquid seal valve 102—103 and pass into the liquor drain and collecting main 84. This spray device effects the cooling of the gases from both offtakes and prevents the decomposition of the rich gases 45 by heat and the objectionable precipitation of pitch, the formation of which would otherwise tend to clog the piping system. The reverse steam nozzle 95¹ projects a column of steam outwardly through the offtake pipe 81 50 preventing its undue expansion and consequent disruption of the wall structure. This steam is subsequently condensed in the stand pipe, this operation being facilitated and the further purification of the gases being affected 55 by the downwardly directed spray 94 in the upper gas collecting main.

When it is desired to regulate the quantity of lean gas from the lower offtake to be 60 mixed with the richer gases from the upper offtake, the lower valve 102—103 is opened

permitting the excess lean gas from the lower offtake to pass with the flushing liquor into the lower collecting main 84 and the quantity passing upward and mixing with the richer gases from the upper offtake may be regulated by manipulation of the butterfly valve 93 and the control of the relative pressures in the collecting mains 83 and 84.

When it is desired to take the gases off separately, the valve 98—99 is closed, the valve 75 102—103 remaining open. The rich gases from the upper offtake will then pass to the upper gas collecting main 83 while the leaner gases from the lower offtake will pass with the fluid residue into the lower collecting main 84 and hence after further purification 80 conveyed to the heating flues or other points where it may be utilized.

The invention as hereinabove set forth or exemplified may be variously practiced or embodied within the scope of the claims herein-after made.

I claim:

1. In a coking retort oven, in combination: a coking chamber; an upper gas offtake leading therefrom; a gas collecting main; a standpipe connected at its upper end with said offtake and said main; a lower gas offtake leading from said chamber at a point below the point of communication of the upper gas offtake with said chamber and also connected with said standpipe at a point intermediate the ends thereof and spaced from the upper end thereof and communicating through said standpipe with said gas main 95 so that gas from the lower offtake may pass upwardly by the upper offtake and thence with gases therefrom to said main; means adapted for discharging liquid gas purifying medium into said standpipe so that said medium will pass therethrough from below the point of communication of the upper offtake therewith past the point of communication of the lower offtake with the standpipe and thereby may treat, in said standpipe, gas that 100 may pass therein from said lower offtake by said upper offtake before said gas reaches said upper offtake; and a seal for said standpipe disposed below the points of communication of both of the offtakes with said standpipe and adjustable to permit either the medium and precipitates alone, or both the medium and precipitates and gas to pass therethrough; and an additional seal for said standpipe disposed between the points of communication of said offtakes with said standpipe, said additional seal also being adjustable to permit either the medium and precipitates alone, or the medium and precipitates and gas to pass therethrough; substantially as specified.

2. In the combination defined by claim 1, an adjustable valve in the standpipe between the upper offtake and the gas main.

3. In a coking retort oven, in combination:

a coking chamber; a gas offtake leading therefrom; a second gas offtake leading from said chamber at a point below the point of communication of the first mentioned offtake with said chamber; and a duct connection communicably connecting the second mentioned offtake with the first mentioned offtake and arranged between said offtakes exteriorly of said retort oven; means adapted for supplying a gas purifying liquid medium to the duct connection between said offtakes so that such medium will traverse first the point of communication of the first mentioned offtake with the duct connection, then the duct connection and then the point of communication of the second mentioned offtake with the duct connection; and a seal disposed within the duct connection between the points of communication of the offtakes with said duct connection and adapted for passage of the gas purifying medium and precipitates from the first mentioned offtake to the second mentioned offtake while preventing passage of gas from one offtake to the other through said duct connection.

4. The combination defined in claim 3 in which the seal is capable of two adjustments, in one of which it permits the medium and precipitates alone to pass, and in the other of which it permits free passage of the medium and precipitates and also permits free passage of the gas from one to the other of the gas offtakes.

5. In a vertical coking retort oven, in combination: a vertical coking chamber; an upper gas offtake leading therefrom at a point adjacent the top thereof; a gas collecting main located exteriorly of said retort oven and communicably connected with said offtake; a lower gas offtake leading from said chamber at a point below the point of communication of said upper gas offtake with said chamber; a duct connection arranged exterior to and separate from the retort oven and communicably connecting the lower gas offtake with the upper gas offtake so as to communicably connect the lower gas offtake with said main; and means for injecting a cooling liquid into said duct connection and adapted for effecting cooling of gas in the duct connection between the upper offtake and the lower offtake and thereby cool gases that may pass through the duct connection from said lower offtake to the upper offtake, to prevent decomposition of rich gases taken off by the upper offtake by heat of gas from the lower offtake; and a drain adapted for draining spent cooling liquid away separately from the gas main.

6. In a vertical coking retort oven, in combination: a vertical coking chamber; an upper gas offtake leading therefrom at a point adjacent the top thereof; a gas collecting main located exteriorly of said retort oven and communicably connected with said offtake; a lower gas offtake leading from said chamber at a point below the point of com-

munication of said upper gas offtake with said chamber; a duct connection arranged exterior to and separate from the retort oven and communicably connecting the lower gas offtake with the upper gas offtake so as to communicably connect the lower gas offtake with said main; means for injecting a cooling liquid into said duct connection and adapted for effecting cooling of gas in the duct connection between the upper offtake and the lower offtake and thereby cool gases that may pass through the duct connection from said lower offtake to the upper offtake, to prevent decomposition of rich gases taken off by the upper offtake by heat of gas from the lower offtake; and a drain adapted for draining spent cooling liquid away separately from the gas main.

7. In a coking retort oven, in combination: a coking chamber having a wall thereof formed of refractory material and provided with a gas outlet for said chamber; a metallic gas-offtake conduit arranged within said outlet adjacent the refractory material thereof to cover the material forming said outlet from contact with gas passing therethrough; a standpipe communicating with the outer end of said offtake conduit to receive gas therefrom; and a feed pipe extending inwardly axially of the offtake conduit and provided with a reversing nozzle adjacent its inner end for discharging cooling fluid against the portion of the conduit adjacent the refractory material and outwardly to said standpipe.

8. In a coking retort oven, in combination: a coking chamber; a standpipe; liquid injecting means for injecting liquid thereinto; and a gas offtake extending upwardly and outwardly at an angle to the vertical and to the horizontal, from said chamber and connecting said chamber with said standpipe below the means for injecting liquid therein; said offtake being provided with means for preventing liquid from said liquid injecting means from draining from said standpipe through said offtake into said chamber.

9. In a coking retort oven, in combination: a coking chamber; a standpipe; a discharge pipe communicating with and leading downwardly from said chamber to an intermediate point in said standpipe; a gas main communicably connected with said standpipe at a point above the point of communication of the discharge pipe with the standpipe a collection means for liquid from said standpipe; and a liquid valve in said standpipe at a point below the junction of the discharge pipe therewith for permitting continuous downward flow of gas purifying liquid through said standpipe separately from said gas main to said collection means.

10. In a coking retort oven, in combination: a coking chamber; a standpipe; a discharge pipe communicating with and leading downwardly from said chamber to an

intermediate point in said standpipe; a gas main communicably connected with said standpipe at a point above the point of communication of the discharge pipe with the standpipe a collection means for liquid from said standpipe; and a liquid valve in said standpipe at a point below the junction of the discharge pipe therewith for permitting continuous downward flow of gas purifying liquid through said standpipe separately from said gas main to said collection means while preventing that of gas; said valve being adjustable to also permit the flow of gas.

11. In a coking retort oven, in combination: a coking chamber; upper gas-offtake means for taking off gas from the top of said chamber; lower gas-offtake means for taking off gas at a lower level from said chamber the upper offtake means and the lower offtake means being communicably connected with each other by duct means arranged exteriorly of said oven for passage of gas from one to the other of said gas offtake means; gas collecting means for collecting and mixing gases from both of the offtake means in predetermined proportion; and means for reducing in the duct means, between the upper offtake means and the lower offtake means, the temperature of gas from one of the offtake means, whereby to prevent decomposition in the duct means of cooler gas from one of the offtakes by hotter gas from the other offtake.

In witness whereof, I have hereunto set my hand.

JOSEPH VAN ACKEREN.
